United States Patent Office.

ALBERT F. ZIEGLER, OF COLUMBUS, OHIO.

Letters Patent No. 101,202, dated March 22, 1870.

IMPROVEMENT IN VAPOR-BURNERS.

The Schedule referred to in these Letters Patent and making part of the same

To all whom it may concern:

Be it known that I, ALBERT F. ZIEGLER, of the city of Columbus, in the county of Franklin and State of Ohio, have invented a new and useful Improvement in Vapor-Burners; and I do hereby declare that the following is a full and exact description of the same, reference being had to the drawings hereto attached, forming a part of this specification.

The nature of my invention consists in making the gas-chamber and its heating-arms all from a single piece of tubing, thus providing the upper part of my burner with two arms, already grooved on their upper surface and curved in an ogee-form, so as to be adapted for continuous contact with the lower edge of the flame as it is emitted from the burner, thus conforming to the natural contour of the flame, and, by contact for its whole length with the flame, securing from it sufficient heat to volatilize the fluid, generate the gas, and avoid the necessity of a second jet for that purpose.

To enable others skilled in the art to make and use my invention, I will proceed to describe its construction and operation.

Figure I represents a lamp, A, with burner B attached.

Figure II, the burner complete, with its arms C C and openings D D D D.

Figure III, a longitudinal section of gas-chamber E.

Figure IV, generating-chamber F.

Figure V, packing-tube G.

Figure VI, the nib, with slot H, to be placed in the upper part of the gas-chamber E, between the arms C C.

I construct the gas-chamber E, Fig. III, of copper tubing, by sawing or splitting from above downward a sufficient length to form the arms C C. These are then bent outward and upward, as shown in Fig. II, so as to conform with the shape of the flame.

The nib, Fig. VI, is now fitted by a screw into the upper part of the gas-chamber E, between the arms or wings C C.

At the bottom of this chamber are a number of small orifices, D D D D, Fig. II, for the purpose of admitting the atmosphere, which, combined with the gas in proper proportions, insures a perfect combustion and a beautiful white flame.

In the lower end of this chamber is placed a neatly-fitted plug, with a small perforation, O, Fig. III, through its center, connecting with the generating-chamber, Fig. IV.

I construct the generating-chamber F, Fig. IV, also of copper, so as to insure a more perfect diffusion of heat.

The packing-tube G, Fig. V, is made of brass tubing, so as to prevent the charring of the packing and a descent of the heat to the key, it conducting heat in a degree much less than copper.

For packing I use the ordinary candle-wicking, sometimes using a fine wire-gauze on the upper end of packing-tube.

I am aware that separate curved heating-pieces or arms have been brazed or attached to burners, and projecting in opposite directions.

I claim a vapor-burner in which the gas-chamber E and the grooved arms C C are made from a single piece of tubing, cut or split longitudinally far enough to form the arms C C already grooved, and having a nib, H, inserted at the junction of the arms, substantially as and for the purpose set forth.

ALBERT F. ZIEGLER.
